SCREW AND RIVET-LOCK CINCH BINDER

George R. Anderson, Santa Rosa, Calif., assignor
of one-half to E. L. Finley, Santa Rosa,
Calif.

Application December 14, 1931, Serial No. 580,824
Renewed February 12, 1934

2 Claims. (Cl. 129—12)

This invention relates to loose leaf binders and especially to large binders such as are used in municipal and government offices of different kinds and in which valuable data, such as assessment rolls etc. are kept. In the use of such binders it is desirable that the sheets or leaves as inserted therein shall be very firmly held against being torn from place. It is also desirable once the binder is filled or the data for the year or other fiscal term has been placed therein, that the cover of the binder shall be sealed against removal so as to prevent the possible loss or substitution of any of the sheets.

The principal object of my invention therefore is to provide a binder structure by means of which the above desired ends may be obtained in a convenient and practical manner and without the use of any relatively expansive spring locks or other devices which are liable to get out of order and refuse to function; and with which the desired clamping pressure cannot be conveniently obtained, if at all.

A further object of the invention is to produce a simple and inexpensive device and yet one which will be exceedingly effective for the purpose for which it is designed.

These objects I accomplish by means of such structure and relative arrangement of parts as will fully appear by a perusal of the following specification and claims.

In the drawing similar characters of reference indicate corresponding parts in the several views:

Fig. 1 is a perspective view of a binder as partly filled and before the cover is finally sealed.

Fig. 2 is a full-sized fragmentary section of a binder showing the cover clamped against the sheets by the post and nut arrangement.

Fig. 3 is a perspective view of a binding nut detached.

Fig. 4 is an enlarged fragmentary section of the binder cover, post and nut showing the final relation of the nut and its post when the binder is finally sealed.

Fig. 5 is a similar view of a modification showing a nut sealed against turning and removal.

Fig. 6 is a fragmentary view of a sectional form of binding post.

Fig. 7 is a side view of a modified form of binding post.

Fig. 8 is a fragmentary perspective of the lower portion of the same.

Referring now more particularly to the characters of reference on the drawing and particularly at present to Figs. 1 to 5, the numerals 1 and 2 denote the bottom and top back bars of the cov-

ers 3 and 4 respectively, which covers are flexibly or hingedly connected to the bars as usual. The bars are preferably hollow for the sake of lightness and rigidly secured in any suitable manner in the lower bar 1 and projecting upwardly therefrom at spaced intervals along the length of the same are threaded posts 5.

The leaves or sheets 6 to be disposed between the covers are of course punched to correspond to the size and spacing of the posts so as to slip over the same. The posts are of an initial height sufficient to take care of any maximum number of leaves which might be placed in the binder.

The posts project with a running fit only through the bottom wall of the upper bar and through considerably larger holes 7 in the top wall of the bar. The bar therefore may be slipped onto or removed from the posts at any time as long as the posts are clear. To clamp the upper bar against the adjacent leaves or sheets to hold the latter firmly against each other and also prevent removal of the cover, I provide nuts 8 to screw onto the posts. Said nuts are preferably of circular form and of a diameter such that they will fit through the holes 7; while their height is less than the thickness of the bar between the top and bottom walls, so that the top surface of the nuts is below the upper surface of the bar when said nuts are engaged with the lower interior wall of the bar as shown in Fig. 2.

The nuts are provided with opposed slots 9 whereby they may be turned with the aid of a suitable spanner provided for the purpose. Since the nuts are normally removable the cover may be taken off the posts whenever it is necessary to add another sheet, and each time the cover is replaced it is clamped securely against the sheets to hold the same firmly in place and prevent their being torn out from about the posts.

When the binder is to be finally sealed up, so that no more sheets can be added or removed, the cover is temporarily taken off and the posts sawed off to a level such that when the cover is subsequently replaced and tightened down by the nuts, the tops of the posts will be below the top level of the cover bar as shown in Fig. 4. The topmost threads of the posts are then deflected or deformed outwardly by a punch or the like so that some of the metal of the threads will enter the slots 9 as shown at 10 in Fig. 4, thus preventing the nuts from being unscrewed.

In order to provide a positive seal against the removal of the cover and of a nature such that any attempt at tampering will be immediately de-

tected, I cut one post off somewhat shorter than the remainder or so that its upper end will be below the top of the corresponding nut as shown in Fig. 5. The cup thus formed in the nut 8a above the post is then filled with lead etc. as at 11, which being poured in a molten condition of course flows into the spanner slots 9, positively tying the leaden seal to the nut. To prevent the plug of lead from possibly coming out, the nut 10 (which is a special one for the purpose) is undercut below the top as shown at 12 so that the lead will have a dove-tail fit. The holes 7 are then preferably plugged with discs 13 of the same kind of leather or fabric with which the bar 2 is bound so that a smooth and finished surface is presented.

Nothing then projects above the top of the binder to prevent a number of binders being then disposed in close superimposed or side-by-side relation on a shelf or in a bookcase.

In some instances the relatively long posts which initially project some distances above the binder, would be objectionable. If desired therefore the posts may be of the sectional character 25 as shown at 5a in Fig. 6, and of the same general form of construction as now employed for sectional binder posts except that they are threaded from end to end so that when assembled they form a continuous screw.

For certain classes of binders in which a definite number of leaves have a constant definite depth or thickness of the bound matter, I may make the posts of curved and non-threaded form as shown at 14 in Figs. 7 and 8. The lower end 30 of each such post has a cross-head 15 or the like for holding engagement with the bottom bar 1a of the cover. At its upper end the post is provided with a vertical threaded stud 16 projecting into the top bar 2a, leaving a shoulder at the base 40 of the stud on which said bar is supported. The nut to engage the stud is of the same character and may be secured against removal when desired in the same manner as described in connection with the first form of binder post.

From the foregoing description it will be read-

ily seen that I have produced such a device as substantially fulfills the objects of the invention as set forth herein.

While this specification sets forth in detail the present and preferred construction of the device, 80

still in practice such deviations from such detail may be resorted to as do not form a departure from the spirit of the invention, as defined by the appended claims.

Having thus described my invention what I 85 claim as new and useful and desire to secure by Letters Patent is:

1. In connection with a binder structure having top and bottom covers, threaded posts projecting upwardly from the bottom cover and through the top cover, and nuts initially removable and adjustable on the posts to clamp the top cover against the sheets contained between the covers, said nuts having spanner slots on top open to the bore, the method of sealing the cover against removal when the binder is filled consisting in first removing the nuts and top cover, cutting off one of the posts to a level such that it will be below the top of its nut when the cover is replaced and the nut is screwed down, replacing the cover and nut, and flowing an initially molten sealing material into the cup formed between the nut and post and into the spanner slots of said nut to fill the same. 95

2. In a binder, top and bottom covers, threaded posts mounted in the bottom cover and extending through the top cover and nuts for engagement with the posts having initially open spanner slots for engagement with a wrench; the bore of one of said nuts adjacent its upper end being 100 provided with a relatively large annular groove communicating with the slots whereby when the nut is screwed onto its post with the top of the post below the groove and sealing material is flowed into the bore of the nut to fill the same to 115 the top and form a sealing plug, such material will fill the groove and slots and prevent removal of the plug and nut. 110
